UNITED STATES PATENT OFFICE

WILLIAM A. READY, OF BROOKLINE, MASSACHUSETTS

METHOD OF MAKING D-HANDLES FOR SHOVELS AND THE LIKE

Original application filed September 4, 1930, Serial No. 479,666. Divided and this application filed March 9, 1931. Serial No. 521,181.

My invention aims to provide improvements in the method of making D-handles for shovels and the like.

This application is a division of my co-pending application Serial No. 479,666, filed September 4, 1930.

In the drawings which illustrate a preferred embodiment of my invention:—

Figure 1 is an elevation view of my invention showing the upper end of a split stale in-cased in a sheet metal casing, parts of the casing structure being shown in dotted lines;

Fig. 2 is a view of the sheet metal casing before attachment to a stale, the lower portion being in cross-section to show the means which holds the parts of the casing in assembled relation, the reinforcing portions on the inner flanges being shown in their positions before being bent;

Fig. 3 is a section taken on the line 3—3 of Fig. 2;

Fig. 4 is a view of the lower portion of the metal casing showing one method of assembling the stale therewith to bend the reinforcing portion during the assembling operation; and

Fig. 5 is a view of the lower end of one part of the casing as viewed when looking toward the flat face thereof.

With reference to the drawings, I have shown a D-handle which includes a casing 1 preferably formed from sheet metal and combined with the split end of a stale 2 and a grip piece 3, as shown in Fig. 1. The general construction of the handle, except for the means by which the casing parts are secured together, and the method of assembly of the three parts of the handle is substantially the same as shown and more fully described in my co-pending application Serial No. 341,131, filed February 19, 1929. My present invention relates to improvements in the casing and to a method of assembling the stale with the casing to bend the reinforcing members as a part of the assembly operation. Furthermore, my present invention is similar in construction to my co-pending application Serial No. 479,665, filed herewith, and over which the present invention is an improvement. Therefore, I shall describe only so

much of my device as is necessary for a clear understanding of my present invention over the devices and methods more fully explained in the applications referred to above.

The sheet metal casing 1 illustrated in the drawings is formed from two similar hollow sheet metal parts each of which is substantially semi-cylindrical in cross-section and is provided with a flat face formed by flanges 4, 4 bent inwardly and abutting at the center, as shown in Figs. 3 and 4. These inwardly bent flanges 4, 4 terminate a substantial distance from the stale-receiving end of the casing, Figs. 2 and 5, thereby leaving the lower portion open so that when the two pieces are secured together there will be no partition in the center of the casing at the stale-receiving end thereof, as clearly shown in Fig. 2. Each casing part is also provided with a vertical flange 5 at one end of the lower semi-cylindrical portion, while a reinforcing portion 6 is provided at the lower edge of that flange 4 which is located at the opposite side of the vertical axis of the casing part, the purposes of which will be more fully hereinafter described.

The two parts of the casing are assembled together, Fig. 2, in such a manner that the flat face of one part faces the flat face of the other part. Furthermore, the flange 5 of one part overlaps the cylindrical portion of the other part, Fig. 3, and each is welded to secure the parts of the casing in fixed assembly. Each reinforcing portion 6 extends below a flange 4 and projects into a space provided by the D-shaped cross-section of a casing part. These reinforcing portions may be bent upwardly and against the inner faces of the flanges 4, as shown in Fig. 1, prior to insertion of the split stale, or, as will hereinafter be described, may be bent as a part of the assembly operation. The reinforcing portions 6 are provided to prevent spreading of the arms of the casing beyond the lower edges of the flanges 4 when the casing is spread into Y-shaped formation, as shown in Fig. 1. The reinforcing portions 6 also help to prevent accidental splitting of the stale when the handle is subjected to undue stress,

such, for instance, as when the handle is used for a "pry".

The casing which is illustrated and described in my present application is decidedly stronger adjacent to the stake-receiving end than the casing shown and described in my above-mentioned co-pending application Serial No. 341,131, because of the arrangement of the vertical flanges 5 with relation 10 to the reinforcing portions 6. As above stated each part of the casing has been so constructed that the flange 5 is located below one of the flanges 4, while the reinforcing portion 6 is located at the lower end of the other 15 flange 4. Thus, it is possible to provide larger flange portions 5 and reinforcing portions 6 because no portion of one is taken from the flange from which the other is formed. The result is a larger welded area and larger, and 20 therefore more durable, reinforcing portions.

The method of assembling the stake 2 with the casing 1 is, in general, substantially the same as the method more fully illustrated and described in connection with my co-pending 25 application Serial No. 341,131. There is an additional step in the method of assembly of the parts of the present structure, however, inasmuch as the reinforcing portions may be very readily pressed from the position shown 30 in Fig. 2 to the position shown in Fig. 1 by the ends of the arms of the stake 2 when forced into the casing, as clearly shown in Fig. 4. When this method of assembly is followed, the reinforcing portions are clamped tightly 35 between the inner faces of the flanges 4 and the sides of the arms of the stake and are, therefore, back-supported.

My improved D-handle structure is strong, durable and relatively inexpensive both from 40 a standpoint of simplicity of construction and reduction in the number of operations required for assembly of parts of the casing and the stake therewith, especially when the method of upsetting the reinforcing portion 45 is followed as above described.

While I have illustrated and described a preferred embodiment of my invention, I do not wish to be limited thereto, because the scope thereof is best defined by the following claims.

I claim:

1. The method of producing a D-handle which comprises forming a metal part with two separate parallel hollow arms secured 55 together at their lower ends and having reinforcing portions extending into the hollow arms at the upper end of the portion where they are secured together, forcing means into the hollow arms thereby bending the reinforcing portions into positions for reinforcing 60 the connection between the hollow arms, bending the arms and means forced into them into diverging relation and securing a grip piece between the diverged ends of the arms.

65 2. The method of producing a D-handle

which comprises forming a metal part with two separate parallel hollow arms secured together at their lower ends and having reinforcing portions extending into the hollow arms at the upper end of the portion where they are secured together, dividing one end of a stem longitudinally to provide a pair of connecting portions, forcing the portions into the hollow arms thereby bending the reinforcing portions into positions for reinforcing 70 the connection between the hollow arms, bending the arms and connecting portions forced into them into diverging relation and securing a grip piece between the diverged ends of the arms.

3. The method of producing a D-handle having a metal part comprising two tubular portions each having longitudinal flange portions overlapping the other part at one end of the metal part and having reinforcing 75 portions extending into the hollow tubular portions adjacent to the upper ends of said flanges which comprises securing the two tubular portions together by welding the overlapping flange portions, bending the reinforcing portions into positions for reinforcing 80 the connection between the two tubular portions during the attachment of the metal part to a split stake.

4. The method of producing a D-handle which comprises forming a metal part with two separate parallel hollow arms secured together at their lower ends and having reinforcing portions extending into the hollow arms at the upper end of the portion where they are secured together, forcing means into the hollow arms thereby bending the reinforcing portions into positions for reinforcing 95 the connection between the hollow arms during the operation of attaching the stem 100 to the metal part.

5. The method of assembling a longitudinally divided stake with a metal casing having a center partition dividing the casing into two hollow parts adapted to receive the longitudinally divided portion of the stake and reinforcing portions extending from the partition to intersect the hollow parts of the casing which comprises inserting the longitudinally divided portion of the stake into the casing, the stake portions forcing the reinforcing portions against the partition during their entrance into the hollow parts and then spreading the hollow parts by dividing the partition into a Y-shaped formation to provide a D-handle structure and the said reinforcing portions back-supported by the stake portions preventing spreading of the hollow parts or splitting of the stake beyond their points of connection with the partition.

6. The method of reinforcing a D-handle structure having a casing divided throughout the greater portion of its length into two hollow arms having flat inner faces and a stake split to provide arms entering the hol- 120

low arms of the casing which comprises providing reinforcing portions extending from the lower edges of the flat inner faces of the casing and intersecting the hollow arms and bending the said reinforcing portions over the edges and against the inner faces of the opposed flat faces by means of forcing the arms of the split stale into the hollow arms, said reinforcing portions thereby preventing spreading of the casing or splitting of the stale beyond their point of connection with lower edges of the edges of said flat faces.

In testimony whereof, I have signed my name to this specification.
